BEAM LOCK

Filed Oct. 16, 1937

FIG. 4 Inventor:
MOTEN E. TANNER

284

James E. Tanner
Attorney

This invention relates to a beam lock for looms which is used for holding the journals of a warp beam shaft securely in the bearings. In the operation of looms considerable wear is caused on the journal of the warp beam shafts, resulting in a loose fit between the shaft and its bearings. When the loom is in operation, vibration of the entire beam will, therefore, take place and affect the tension of the warp, which, in turn, will produce

10 a defective cloth.
It is, therefore, an object of this invention to provide a simple and efficient beam lock which is capable of adjustment to hold the warp beam for rotation and yet eliminate this play. This particular form comprises a bearing cap which is bodily movable relative to the bearing and which may be adjusted thereon to compensate for any wear which takes place upon the journals of the warp beam or upon the bearings in which they 20 rotate, or to accommodate different sizes of journals.

It is a further object of this invention to provide a beam lock which can be quickly and efficiently operated when it is desired to remove and replace 25 a warp beam and which permits the removal of the same without detaching the beam lock from the frame of the loom.

Some of the objects having been stated, other objects will appear as the description proceeds 30 when taken in connection with the accompanying drawing, in which:

Figure 1 is an elevation of an end portion of a warp beam, associated with a loom frame and showing my invention applied thereto;

35 Figure 2 is a vertical, sectional view taken along the lines 2-2 in Figure 1;

Figure 3 is a sectional, plan view taken along the line 3-3 in Figure 1;

Figure 4 is an exploded isometric view of the 40 beam lock and its associated bearing;

Figure 5 is an inverted isometric view of the beam lock cap.

Referring more specifically to the drawing the 45 numeral 10 denotes a warp beam which has a head 11, friction drum 12, and a central shaft 13, said shaft having a restricted end journal portion 14. The portion 13 is adapted to rotate in semi-circular bearing portion 15, which portion is integral with the upper portion of bracket 16. This 50 bracket is secured to the side-frame 17 of a loom by any suitable means such as bolts 18, which bolts are adapted to penetrate slots 19 in the brackets, and also the frame 17 of the loom. The bracket 16 also has a rest portion 20 which is adapted to 55 receive the journal of the loom beam shaft before

the beam is placed into the bearing portion 15. This portion also acts as a rest for the ends of the shaft when removing the loom beam.

Although only a portion of one side of a loom is shown in the drawing, it is evident that a similar bearing is placed on the other side for supporting the other end of the warp beam. This part on the other side is identical, except that it is opposite handed and therefore, a showing and description is not thought to be necessary. 10

When the journals of the beam are placed in the bearings 15 it is then necessary to clamp the upper side thereof tightly in position. At this time, a semi-circular bearing cap 21 is placed upon the upper side of portions 13 and 14 of the 15 warp beam shaft, said bearing portion being integral with one side of lever 23 and extending laterally therefrom. This lever has a suitable slot 24 therein which is normally penetrated by a bolt 25. This bolt is also adapted to penetrate hole 26 in 20 the bracket 16. The other end of the lever 23, that is the end nearest the observer in Figures 1 and 3, has a down turned hook portion 27, and this hook portion is adapted to fit underneath flange 16a of bracket 16 when the cap is in a fixed 25 position. When it is desired to adjust the bearing cap 21 and lever 23 so as to compensate for the wear between the bearing portion 15 and the journals 13 and 14, it is only necessary to loosen the nut on bolt 25 and rotate the lever 23 in a 30 counterclockwise manner (Figure 2) about the hook portion 27 and then again tighten the same.

On the other hand, when it is desired to remove the warp beam from the bearing 15, it is only necessary to loosen the nut on bolt 25 so that the 35 hook portion 27 may be pulled laterally out from beneath the outstanding flange 16a. Then the lever 23 along with the bearing cap 21 may be rotated in a counter-clockwise manner about bolt 25 until the ends of the warp beam shaft may be 40 removed.

By observing Figure 5 it is seen that the bearing portion 21a of lever 23 is of a slightly greater radius than the bearing portion 21b. This difference in the bearing portion is provided so that 45 a suitable shoulder 21c will be present when the lever 23 and cap 21 are in a fixed position in order to prevent longitudinal movement of the beam shaft 13 and its restricted portion 14. Of course, the radius of the bearing portion 21a is 50 substantially the same as the radius of portion 13 of the beam shaft, whereas the radius of the portion 21b is substantially the same as that of the restricted portion 14 of this same shaft.

It is thus seen that I have provided a beam rest 55

UNITED STATES PATENT OFFICE

BEAM LOCK

Moten E. Tanner, Spartanburg, S. C.

Application October 16, 1937, Serial No. 169,342

2 Claims. (Cl. 308-24)

This invention relates to a beam lock for looms which is used for holding the journals of a warp beam shaft securely in the bearings. In the operation of looms considerable wear is caused on the journal of the warp beam shafts, resulting in a loose fit between the shaft and its bearings. When the loom is in operation, vibration of the entire beam will, therefore, take place and affect the tension of the warp, which, in turn, will produce

10 a defective cloth.
It is, therefore, an object of this invention to provide a simple and efficient beam lock which is capable of adjustment to hold the warp beam for rotation and yet eliminate this play. This particular form comprises a bearing cap which is bodily movable relative to the bearing and which may be adjusted thereon to compensate for any wear which takes place upon the journals of the warp beam or upon the bearings in which they 20 rotate, or to accommodate different sizes of journals.

It is a further object of this invention to provide a beam lock which can be quickly and efficiently operated when it is desired to remove and replace 25 a warp beam and which permits the removal of the same without detaching the beam lock from the frame of the loom.

Some of the objects having been stated, other objects will appear as the description proceeds 30 when taken in connection with the accompanying drawing, in which:

Figure 1 is an elevation of an end portion of a warp beam, associated with a loom frame and showing my invention applied thereto;

35 Figure 2 is a vertical, sectional view taken along the lines 2-2 in Figure 1;

Figure 3 is a sectional, plan view taken along the line 3-3 in Figure 1;

Figure 4 is an exploded isometric view of the 40 beam lock and its associated bearing;

Figure 5 is an inverted isometric view of the beam lock cap.

Referring more specifically to the drawing the 45 numeral 10 denotes a warp beam which has a head 11, friction drum 12, and a central shaft 13, said shaft having a restricted end journal portion 14. The portion 13 is adapted to rotate in semi-circular bearing portion 15, which portion is integral with the upper portion of bracket 16. This 50 bracket is secured to the side-frame 17 of a loom by any suitable means such as bolts 18, which bolts are adapted to penetrate slots 19 in the brackets, and also the frame 17 of the loom. The bracket 16 also has a rest portion 20 which is adapted to 55 receive the journal of the loom beam shaft before

and lock which is capable to being attached to any loom, and also which enables an operator to remove the beam easily and quickly, without entirely detaching the beam lock from the frame 5 of the loom.

I have also provided a beam rest which tightly clamps the ends of the loom beam to the bearings and prevents undue vibration from taking place in the bearings, yet permitting the rotation of the 10 warp beam.

In the drawing and specifications there has been set forth a preferred embodiment of the invention, and although specific terms are employed, they are used in a generic and descriptive 15 sense only, and not for purposes of limitation, the scope of the invention being set forth in the appended claims.

I claim:

1. In a loom having a pair of brackets secured 20 to the frame of the loom and each being provided with an upwardly opening semi-circular cavity to serve as a bearing portion for the journals of a warp beam, and also having a rib projecting from one side thereof, means for releasably lock- 25 ing the journals in said cavities for rotation, comprising a member provided with a downwardly opening semi-circular bearing portion, said member having an inturned hook on one end

adapted to fit beneath said rib on the bracket and having a vertically disposed slot in its other end, a bolt penetrating said slot and said bracket, which bolt when its nut is driven home serves to hold the hook beneath the rib on the bracket 5 and to thus hold the member in a position to confine the journals of the warp beam in said semi-circular cavities.

2. In a loom having a pair of parallel spaced brackets provided with semi-circular upwardly 10 opening bearing portions for reception of the journals of a warp beam, and having holes in one end for securing the same to a loom frame, each bracket having an outwardly projecting rib along the outer upper edge thereof, a member associated with each bracket for holding the journals in said semicircular bearing portions, said member having a semi-circular bearing portion along 15 its lower edge and having a vertically disposed slot in one end and having a laterally projecting 20 lip on its other end adapted to fit beneath said rib on said bracket, and a bolt penetrating the slot in the bracket and said slot in the member for holding one end of the member against said bracket and for also holding said laterally projecting lip beneath said rib to prevent upward 25 and lateral movement of the said member.

MOTEN E. TANNER.
